CHARLES W. FAILOR, OF FOREST HILLS, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed September 27, 1929. Serial No. 395,488.

This invention relates to railway traffic controlling apparatus, and particularly to apparatus for supplying coded train control energy to the rails adjacent both ends 5 of a section of railway track. One of the features of the invention resides in novel provisions for causing a single coding device to supply train control energy alternately to the rails adjacent both ends of a track 10 section, the application of such coded energy adjacent each of said ends being furthermore controlled in accordance with traffic conditions beyond said end. The invention also comprises means controlled by the application of coded energy for increasing the 15 impedance of the circuit of a track relay connected to the track section, and thereby to prevent the energization of said track relay upon the application of coded energy 20 to the adjacent end of the track section. Other features of the invention will be hereinafter described and claimed.

The accompanying drawing consists of a diagrammatic view illustrative of my invention.

Referring to the drawing, the reference character 5 designates a section of railway track provided with a track relay 6. Winding 6' of relay 6 is connected across the 30 rails adjacent one end of section 5, and the other winding 6'' of the relay is constantly supplied with alternating current from terminals B and C of a suitable source of energy not shown in the drawing. The track 35 relay 6 is normally energized via the rails by current from a track transformer 7, the secondary of which is connected with the rails adjacent the opposite end of the section. Uninterrupted alternating current is 40 normally supplied to transformer 7 over a circuit from terminal B, through wire 10, front contact 11 and armature 12 of relay 6, wire 13, primary of transformer 7, and wire 14 to terminal C. Connected in circuit 45 with winding 6' of track relay 6 is the primary of an impedance transformer 15, the secondary 15' of which is normally shunted by the following circuit: wire 16, armature 17 and back contact 18 of relay 19, wire 20, 50 and said secondary 15'.

When a train enters the track section 5, the relay 6 becomes de-energized, and its armature 12 thereupon engages back contact 21. At the same time, an armature 22 of said track relay 6 engages back contact 23, thereby establishing a circuit from terminal B, through said back contact 23 and armature 22, wires 24 and 25, motor coder 26, and wire 27 to terminal C. The motor coder 26 may be of the well-known type comprising an electric motor and means such as a plurality of make and break cams driven thereby for causing the opening and closing of contacts at different frequencies. In the drawings, there are indicated two contact 65 elements 28, 29, operable by the motor coder. A branch 30 of wire 24 feeds current to said contacts 28, 29 when relay 6 is de-energized. Contact element 28, when operated by the motor coder, engages the contacts 31, 32, 70 alternately; each of said contacts being engaged by said element 28 a given number of times per minute, 180 for example. Similarly, the contact element 29 is operated by the motor coder to engage the contacts 75 33, 34, alternately, and at a different rate than that at which contacts 31, 32 are engaged by element 28; each of the contacts 33, 34 being engaged for example, 80 times per minute by the member 29.

It will be seen that when, upon de-energization of the relay 6, the armature 12 engages back contact 21, the primary of transformer 7 is connected to wire 35, which in turn is connected to armature 36 of a relay 85 37. This armature is adapted to engage either a front contact 38 connected to contact 32, or a back contact 39, connected to contact 34. The relay 37 is responsive to traffic conditions in the section of track to the left of section 5, said relay 37 being energized when traffic conditions to the left of section 5 are safe and de-energized when said conditions are unsafe. Since connections for rendering relay 37 responsive to traffic 90 conditions as above outlined are well known in the art, they need not be here disclosed. When relay 37 is energized, and when the track relay 6 is de-energized, a circuit is 95 closed through the primary of transformer 100 15'.

7 as follows: from terminal B through back contact 23 and armature 22 of relay 6, wires 24 and 30, contacts 28 and 32 of motor coder 26, (each time that contact 32 is engaged by element 28), front contact 38 and armature 36 of relay 37, wire 35, back contact 21 and armature 12 of relay 6, wire 13, primary of transformer 7, and wire 14 to terminal C. Current is thus supplied by transformer 7 to the rails at the left hand end of track section 5, said current consisting of intermittent impulses corresponding to the frequency at which contact element 28 of the motor coder engages contact 32. Should relay 37 be de-energized when relay 6 is de-energized, current is supplied to the primary of transformer 7 from terminal B, through back contact 23 and armature 22 of relay 6, wires 24 and 30, contacts 29 and 34 of motor coder 26, (each time that said contacts are in engagement), back contact 39 and armature 36 of relay 37, wire 35 and thence as before through primary of transformer 7 to terminal C. Such current consists of impulses corresponding to the frequency at which contact element 29 engages said contact 34.

Connected to the rails at the right hand end of the track section 5 is the secondary 30 of a transformer 40, the primary 40' of which is connected by a wire 41 with an armature 42 of a relay 43. The latter, as is well understood in the art, is connected so as to be responsive to traffic conditions 35 to the right of track section 5. When said traffic conditions to the right of section 5 are safe, relay 43 is energized, and when unsafe, said relay is de-energized.

The front and back contacts 44, 45 of relay 40 43 are connected to contacts 31, 33, respectively, of the motor coder. It will thus be seen that when relay 43 is energized and when relay 6 is de-energized, current flows from terminal B, through back contact 23 and armature 22 of relay 6, wires 24 and 30, contact element 28 and contact 31 of motor coder 26, (each time that said contacts are in engagement), front contact 44 and armature 42 of relay 43, wire 41, primary 40' of transformer 40, and wire 46 to terminal C, whereby coded energy comprising impulses corresponding to the frequency of engagement of contact element 28 with contact 31 is supplied to the right hand end of the track section 5. Likewise when relay 43 is de-energized at the time relay 6 is de-energized, coded current comprising impulses corresponding to the frequency of engagement of contact element 29 with contact 33 is supplied through transformer 40 to the rails adjacent the right hand end of section 5, over a circuit which will be obvious from the drawing.

It will be noted that when current is supplied through contacts of the motor coder

by way of wire 41 to transformer 40, current also flows from said wire through wire 47, relay 19, and wires 48 and 46, to terminal C, thereby energizing relay 19 so that its armature 17 is disengaged from contact 18. When this happens, secondary 15' of transformer 15 is open-circuited, and the consequent increased impedance in the primary winding of transformer 15 prevents any considerable amount of energy from flowing through the track coil 6' of relay 6. In addition, any energy from transformer 40 that feeds through the track coil 6' of relay 6 will be in such direction as to open said relay. Thus, the feeding of energy to the track transformer 40 is precluded from picking up the track relay 6.

During the occupancy of the track section by a train the relay 19 operates intermittently and in accordance with the impulses supplied by the motor-coder contacts through wire 41 to transformer 40; the armature 17 of said relay being disengaged from contact 18 whenever an impulse of current is supplied over wire 41 to transformer 40 and said armature returning into engagement with contact 18 as soon as said impulse ceases. While said relay 19 responds to current supplied over wire 41 said relay is so designed as to be non-responsive to current supplied to the rails by transformer 7 at the left hand end of the track section. As has been noted, the impulses supplied to transformers 7 and 40 are supplied thereto alternately; and upon the vacating of the track section the next impulse applied to the rails by transformer 7 will energize the relay 6, the relay 19 being deenergized and armature 17 engaged with contact 18 at the time said impulse is supplied through transformer 7, so that the secondary 15' of transformer 15 is shunted and the impedance of said transformer decreased. This energization of said track relay 6 by the impulse received from transformer 7 disengages armature 22 from contact 23 and re-engages armature 12 with contact 11. As a result, the motor coder becomes de-energized, and the transformer 7 is connected directly with terminals B and C, so as to supply uninterrupted current to the track section 5. The track circuit has thus been restored to normal condition.

From the foregoing description it will be seen that I have provided for the feeding of coded energy alternately to the rails adjacent the respective ends of the track section. This coded energy may be utilized in any suitable or convenient way, as by the usual apparatus mounted on the front of the locomotive and responsive to current impulses applied to the rails of the track section at a point ahead of the train, for causing indications corresponding to said impulses to be given in the locomotive cab. It will be

apparent that by applying coded energy through transformer 7 to the rails at the left hand end of the section in accordance with traffic conditions to the left of said 5 section, a train entering said section from the right (and equipped with the conventional receiving apparatus aforesaid) will receive indications of said traffic conditions; while, conversely, if such train enters said 10 section from the left, it will receive from the impulses applied to the rails by transformer 40 indications of traffic conditions to the right of said section.

The terms and expressions which I have 15 employed are used as terms of description and not of limitation, and I have no intention, in the use of such terms and expressions, of excluding any mechanical equivalents of the features shown and described 20 or portions thereof, but recognize that various structural modifications are possible within the scope of the invention claimed.

What I claim is:—

1. In combination, a section of railway 25 track, a track relay connected with the rails of said track section, means controlled by said relay for applying train control energy to said section, a transformer having a primary winding in circuit with said relay, and 30 a relay controlled by said energy applying means, the secondary winding of said transformer being controlled by said second relay.

2. In combination, a section of railway 35 track, a track relay provided with a circuit including the rails of said track section, means controlled by said relay for applying train control energy to the rails of said section, and means responsive to the application 40 of train control energy to said section for increasing the impedance of the track relay circuit.

3. In combination, a section of railway 45 track, a track relay connected with the rails of said track section, means controlled by said relay for applying train control energy to the rails adjacent the ends of said section, a winding in circuit with said relay, and means controlled by the application of 50 train control energy for varying the impedance of said winding.

4. In combination a section of railway 55 track, a track relay connected with the rails of said track section, means controlled by said relay for applying train control energy to the rails adjacent the ends of said section, a transformer having its primary winding in circuit with said track relay, a relay controlled by said energy applying means, and 60 a circuit for the secondary of said transformer controlled by said relay.

5. In combination, a section of railway 65 track, a track relay connected with the rails of said track section, means effective upon de-energization of said relay for applying

interrupted train control impulses to said track section, a transformer having its primary winding in circuit with said relay, a relay arranged to be energized during each such train control impulse, and a circuit for the secondary winding of said transformer including a front contact of said relay. 70

6. In combination, a section of railway track, a track relay provided with a circuit including at least one rail of said track section, means controlled by said relay for applying train control energy to the rails adjacent the ends of said section, and relay means controlled by said energy applying means for controlling the impedance of the 80 track relay circuit. 75

7. In combination, a section of railway track, a coding device, a track relay connected with the rails of said section and responsive to the entry of a train into the track section for causing said coding device to supply coded energy to the rails adjacent the respective ends of said section, and means controlled by the transmission of energy by said coding device to one end of the track 85 section for varying the impedance of the track relay circuit. 80

8. In combination, a section of railway track, a coding device, a relay connected with the rails of said section and responsive to the entry of a train into the track section for causing said coding device to supply coded energy to the rails adjacent the respective ends of said section, a winding in circuit with said relay, and means controlled by impulses transmitted by said coding device for varying the impedance of said winding. 90

9. In combination, a section of railway track, a track relay provided with a circuit including at least one rail of said track section, means controlled by said relay for applying train control energy to the rails adjacent the ends of said section, and means responsive to the transmission of energy by said first mentioned means to one end of 100 said section for increasing the impedance of the track relay circuit. 105

10. In combination, a section of railway track, a track relay connected with the rails of said track section, means controlled by said relay for applying train control energy to the rails adjacent the ends of said section, a winding in circuit with said relay, and means responsive to the transmission of energy by the first mentioned means to one end of said section for varying the impedance of said winding. 110 115

11. In combination, a section of railway track, a coding device, means including a contact controlled by said coding device for supplying coded energy to the rails adjacent one end of said track section, means including another contact controlled by said coding device for supplying coded energy to the 120 125 130

rails adjacent the other end of said section, a track relay connected to one end of said track section and responsive to the entry of a train into said section for bringing said coding device into action, and means electrically connected to one of said contacts for increasing the impedance of the track relay circuit as an incident to the application of coded energy to the corresponding end of the 10 track section.

12. In combination, a section of railway track, a coding device, means including a set of contacts controlled by said coding device for supplying to the rails adjacent one end 15 of the track section impulses of different frequencies in accordance with traffic conditions beyond said end, means including another set of contacts controlled by said coding device for supplying to the rails adjacent the other end of the track section impulses of different frequencies in accordance with traffic conditions beyond that end, a track relay connected to one end of the track section and responsive to the entry of a 20 train into said section for bringing said coding device into action, and means electrically connected to one of said sets of contacts for increasing the impedance of the track relay circuit as an incident to the application 25 of impulses of any of a plurality of frequencies to the corresponding end of the track section.

13. In combination, a section of railway track, a coding device, means including a set 30 of contacts controlled by said coding device for supplying to the rails adjacent one end of the track section impulses of different frequencies in accordance with traffic conditions beyond said end, means including another set of contacts controlled by said coding device for supplying to the rails adjacent the other end of the track section impulses of different frequencies in accordance with traffic conditions beyond that end, a track relay connected to one end of the track section and responsive to the entry of a train into said section for bringing said coding device into action, and a relay electrically connected to one of said sets of contacts 45 for increasing the impedance of the track relay circuit as an incident to the application of impulses of any of a plurality of frequencies to the corresponding ends of the track section.

14. In combination, a section of railway track, a coding device, means including a set 50 of contacts controlled by said coding device for supplying to the rails adjacent one end of the track section impulses of different frequencies in accordance with traffic conditions beyond said end, means including another set of contacts controlled by said coding device for supplying to the rails adjacent the other end of the track section impulses of different frequencies in accordance 55

with traffic conditions beyond that end, a track relay connected to one end of the track section and responsive to the entry of a train into said section for bringing said coding device into action, and a relay electrically connected to one of said sets of contacts for increasing the impedance of the track relay circuit as an incident to the application of impulses of any of a plurality of frequencies to the corresponding end of the track section. 70 75

15. In combination, a section of railway track, a coding device, a track relay connected with the rails of said section and responsive to the entry of a train into the 80 track section for causing said coding device to supply coded energy to the rails adjacent the respective ends of said section, and a relay controlled by the transmission of energy by said coding device to one end of the track 85 section for increasing the impedance of the track relay circuit.

16. In combination, a section of railway track, a coding device, a relay connected with the rails of said section and responsive to the entry of a train into the track section for causing said coding device to supply coded energy to the rails adjacent the respective ends of said section, a winding in circuit with said relay, and means controlled by 90 impulses transmitted by said coding device 95 for varying the impedance of said winding.

17. In combination, a section of railway track, a winding, a track relay connected with the rails of said section through said 100 winding, a transformer having its secondary connected with the rails of said section, means controlled by said relay for at times supplying coded energy to the primary of said transformer, and a second relay connected with said primary for varying the 105 impedance of said winding.

18. In combination, a section of railway track, an impedance transformer, a track relay connected with the rails of said section through one winding of said impedance transformer, a second transformer having the secondary connected with the rails of said section, means controlled by said track relay for at times supplying coded energy 110 to the primary of said second transformer, a second relay connected with said primary, and a circuit for the remaining winding of said impedance transformer controlled by 115 said second relay.

In testimony whereof, I have signed my name to this specification this 25th day of September, 1929.

CHARLES W. FAILOR.
